INDUSTRIAL RESEARCH CORPORATION, OF TOLEDO, OHIO, A CORPORATION OF
DELAWARE.

FUEL-TANK.

1,364,841.

Specification of Letters Patent.

Patented Jan. 4, 1921.

Application filed July 25, 1918. Serial No. 246,698.

To all whom it may concern:

Be it known that we, CHARLES F. GREEN and HARRY W. LINDSEY, Jr., citizens of the United States, residing at Toledo, in the county of Lucas and State of Ohio, have invented certain new and useful Improvements in Fuel-Tanks, of which we declare the following to be a full, clear, and exact description:

10 Our invention relates to improvements in fuel tanks and, more particularly, to gasoline supply tanks for automobiles and the like and has for its object to provide improved means for preventing the consumption of the full supply of fuel by the engine without first requiring the driver to operate the mechanism controlling that portion of the liquid in the tank constituting the reserve supply and thereby calling his attention to the fact that it is necessary to obtain a fresh supply of fuel.

15 A further object of the invention is to provide an improved valve arrangement for controlling the supply of liquid from a tank 20 having a compartment for holding a reserve supply of fuel.

25 Further objects, and objects relating to economies of manufacture and details of construction, will definitely appear from the 30 detailed description to follow.

35 We accomplish the objects of our invention by the devices and means described in the following specification. Our invention is clearly defined and pointed out in the appended claims.

A structure constituting a preferred embodiment of our invention is illustrated in the accompanying drawings, forming a part of this specification, in which:

40 Figure I is a view in elevation showing the supply tank in section and indicating the manner of connecting the same with the engine through a vacuum feed tank.

45 Fig. II is an enlarged, fragmentary sectional elevation of the supply tank taken on line II-II of Fig. I.

Fig. III is an enlarged, detail, sectional view taken on line III-III of Fig. I.

50 Fig. IV is an enlarged, detail elevation of the valve operating mechanism shown in the upper part of Fig. II.

Fig. V is a sectional plan taken on line V-V of Fig. IV, and,

Fig. VI is an enlarged, detail, side eleva-

tion of the pivotal support for the valve operating lever.

Referring to the drawings, 10 represents an automobile engine or motor of any preferred type, the carburetor and manifold thereof being indicated at 11 and 12 respectively.

The vacuum gravity feed tank 13 of any well known design is connected with the carburetor and manifold by the conduits 14 and 15 respectively, as shown in Fig. I, the vacuum tank being also connected with the fuel supply tank 16 by means of the conduit 17.

The supply tank is provided with a transverse wall or partition 18 which divides the lower part of the tank into two separate compartments 19 and 20, the latter serving as the reserve supply compartment for holding a predetermined quantity of liquid when the entire supply in the remaining portion of the tank has been consumed by the engine. The partition 18 preferably extends upwardly something less than half of the height of the tank and is straddled by a forked pipe having the branches 21 and 22 extending downwardly from the connection 23 which communicates with the supply pipe or conduit 17 through the elbow 24 and short pipe 25 extending through the top of the tank and the plate 26 thereon, as shown in Fig. II.

The pipe 25 exteriorly of the tank is provided with a fixed collar 27 having the spaced arms 28 which are engaged on their inner faces by the laterally extending rounded projections 29 at one end of the lever 30 which is provided with the pivot pin 31 journaled in the upstanding lug or bracket 32 on the plate 26, as shown in Figs. IV and V.

95 The lever is provided with a handle 33 and on its sides adjacent the upstanding lug with a locking projection 34 adapted to engage the lug in the notches or recesses 35 and 36, when said lever is in its extreme operative positions, as shown by the full and dotted lines in Fig. IV.

A spring 37 is mounted on the pivot pin with one end seated upon the lug 32 and the other seated upon the washer 38 which is held by the cotter 39 extending through the outer end of the pin, the spring serving to yieldingly hold the lever in either of the

positions indicated in Fig. IV when the locking projection 34 is in one or the other of the notches 35 and 36.

Upon the bottom end of the branch pipe 21 is secured the valve housing or casing 40 for receiving the ball valve 41 on the stem 42 extending upwardly from the plate 43 which normally rests upon the bottom of the tank when said valve is open. The pipe 21 is 5 extended into the housing, as shown in Fig. III and is suitably connected therewith. The housing is provided with a seat 44 for the valve 41 whereby the branch pipe 21 is closed when the lever is in the position shown 10 in dotted lines in Fig. IV. A spring 45 is mounted upon the stem 42 beneath the casing 40 and serves to insure proper contact of the valve upon its seat when the pipe 21 is elevated by the downward movement of 15 the lever handle 33.

The branch pipe 22 leading to the reserve supply compartment 20 is also provided with a valve housing or casing, as indicated at 46, in which is secured the valve seating 25 member 47 provided with an aperture 48 adapted to be closed by the ball valve 49 rigidly connected with the stem 50 extending upwardly from the plate 51, which is seated upon the bottom of the tank where 30 said valve is closed. The pipe 22 is extended into the upper end of the valve casing and is suitably connected therewith. In the lower portion of the casing is secured the ring 52 for seating the upper end of the 35 spring 53, the lower end of which is seated upon the plate 51 with which the valve stem 50 is connected. The spring 53 serves to assist in unseating the valve 49 when the lever handle is moved to the position indicated by dotted lines in Fig. IV.

When the valve 49 is closed, none of the fuel can be withdrawn from the reserve supply compartment 20 of the tank when suction is produced in the vacuum tank 13 by 45 the engine for the purpose of lifting the liquid from the main supply tank above the top of the partition 18 and below the same from the compartment 19 on the side opposite the partition to that upon which the 50 pipe 22 extends.

It will be readily seen from the drawings that when the lever is in the position shown in Fig. II that the valve 41 will be unseated or opened and the valve 49 closed and that 55 none of the liquid can be withdrawn from the compartment 20 until the lever is moved to the position shown by dotted lines in Fig. IV.

When the branch pipes 21 and 22 and 60 short pipe 25 are elevated by pressing down upon the handle of the lever to cause the upper projection 29 thereof to travel upon the inner face of the upper arm 28 of the collar 27, the valve 41 will be closed and the 65 valve 49 opened to permit the withdrawal

of the reserve supply of liquid by the suction produced in the tank when the engine is running. By closing the valve 41 when the valve 49 is open, the suction of air through the branch pipe 21 is prevented, 70 which is very necessary in a device of this kind. The movement of the lever from its normal position, as shown in Figs. II and IV, will, of course, only be necessary in cases where the driver of the machine fails 75 to replenish his fuel supply at the proper time, either inadvertently or through necessity, as may sometimes be the case. In either of the positions the lever is moved to, it will be firmly held by the locking projection 34 80 engaging the lug 32 in the recesses 35 and 36 under the pressure exerted by the spring 37, as will be readily understood. When the lever handle is in the position shown by dotted lines in Fig. IV, the plates 43 and 51 85 upon which the springs 45 and 53, respectively, are seated will be raised sufficiently to clear the bottom of the tank, the spring 45 serving at this time to close the valve 41 and the spring 53 to open the valve 49 to 90 permit the reserve supply of fuel to be drawn through the pipes 22, 25 and 17.

We are aware that the particular embodiment of our invention, which we have here shown and described, is susceptible of considerable variation, without departing from the spirit thereof, and, therefore, we desire to claim the same broadly, as well as specifically, as indicated by the appended claims. 95

Having thus described our invention, 100 what we claim as new and desire to secure by Letters Patent, is:

1. A device of the class described, comprising a tank having oppositely arranged liquid holding compartments, an adjustable 105 tubular member adapted to alternately communicate with each of said compartments when in different positions of adjustment, and means for adjusting said member relatively to said tank.

2. A device of the class described, comprising a tank having oppositely arranged liquid holding compartments, an adjustable tubular member adapted to alternately communicate with each of said compartments 115 when in different positions of adjustment, means for adjusting said member relatively to said tank, and means for locking the same in adjusted position.

3. A device of the class described, comprising a tank having oppositely arranged liquid holding compartments, a conduit having a branch pipe leading to each of said compartments, and means for shifting said branch pipes to effect the alternate opening 120 and closing of the same.

4. A device of the class described, comprising a tank having oppositely arranged liquid holding compartments, a conduit having a branch pipe leading to each of said 125

compartments, means for shifting said branch pipes to effect the alternate opening and closing of the same, and means for effecting the forcing of the liquid through each of said pipes when open and through said conduit.

5 5. A device of the class described, comprising a tank having oppositely arranged liquid holding compartments, a conduit having a branch pipe leading to each of said compartments, valves coöperating with said branch pipes to control the supply of liquid therethrough, a lever connected with the pipes for moving the same to effect the alternate 10 opening and closing of the valves, and means for effecting the forcing of liquid through each of said pipes and said conduit.

15 6. A device of the class described, comprising a tank having oppositely arranged liquid holding compartments, a conduit having a branch pipe leading to each of said compartments, separate valves coöperating with each of said branch pipes to control the supply of liquid therethrough, means 20 for effecting the alternate opening and closing of the valves, and means for effecting the forcing of liquid through each of said pipes and said conduit.

25 7. A device of the class described, comprising a tank having oppositely arranged liquid holding compartments, a conduit having a branch pipe leading to each of said compartments, valves movable relatively to said tank and coöperating with said branch 30 pipes to control the passage-ways therethrough, means for moving the pipes to effect alternate opening and closing of the same by the valves, and means for effecting the forcing of liquid through each of said pipes when 35 40 open and through said conduit.

45 8. A device of the class described, comprising a fuel tank having a partition therein, a conduit having a branch pipe leading to each side of said partition, and a separate valve for each of said branch pipes, means 45 for simultaneously effecting the alternate opening and closing of said valves.

50 9. A device of the class described, comprising a fuel tank having a partition therein, a conduit having a branch pipe leading to each side of said partition, separate valves for alternately opening and closing said branch pipes, and means for simultaneously shifting the pipes upon the valves.

55 10. A device of the class described, comprising a fuel tank having a partition therein, a conduit adjustable relatively to the tank and having a branch pipe leading to each side of the partition, valves for alternately opening and closing said pipes when the conduit is in different positions of adjustment, and means for shifting and locking said conduit upon the tank.

60 11. A device of the class described, com-

prising a fuel tank having a partition di- 65 viding the lower portion thereof into two compartments, a conduit having a branch pipe leading to each of said compartments, valves seated upon the tank for alternately opening and closing said branch pipes upon 70 movement of the latter, means for shifting the position of said pipes, and means for effecting the forcing of liquid through said pipes.

12. A device of the class described, comprising a fuel tank having a partition therein and an adjustable conduit provided with branch pipes extending into the tank upon each side of the partition, means for alternately opening and closing said branch 80 pipes upon movement of the conduit from one position of adjustment to another, and a lever operatively connected with the conduit for adjusting the same.

13. A device of the class described, comprising a fuel tank having a partition therein, an adjustable conduit provided with branch pipes extending into the tank upon each side of the partition, means for alternately opening and closing said branch 90 pipes upon movement of the conduit from one position of adjustment to another, a member fixed upon the conduit and a lever mounted upon the tank and operatively connected with said member for raising and 95 lowering the conduit.

14. A device of the class described, comprising a fuel tank having a partition therein, an adjustable conduit provided with branch pipes extending into the tank upon 100 each side of the partition, means for alternately opening and closing said branch pipes upon movement of the conduit from one position of adjustment to another, a pair of laterally extending spaced projections carried by said conduit, a lever engaging said projections and movable thereon to effect the adjustment of said conduit, and means for locking said lever in its several 105 positions of adjustment. 110

15. A device of the class described, comprising a fuel tank having a partition therein, an adjustable conduit provided with branch pipes extending into the tank upon each side of the partition, means for alternately opening and closing said branch pipes upon movement of the conduit from one position of adjustment to another, a lever operatively connected with said conduit for adjusting the same, and means for locking the said lever in its several 115 positions of adjustment. 120

16. A device of the class described, comprising a liquid fuel tank, a longitudinally adjustable conduit extending therein, a valve for automatically opening and closing said conduit when in different positions of adjustment, and a lever operatively con-

nected with said conduit for shifting the same.

17. A device of the class described, comprising a liquid fuel tank, an adjustable conduit extending therein, a valve for opening and closing said conduit when the latter is in different positions of adjustment, an upstanding member upon the tank provided with a plurality of notches, a lever 10 pivoted upon said upstanding member and having a locking projection adapted to engage the upstanding member within said notches, means for yieldingly holding the lever upon said upstanding member, and 15 means operatively connecting said lever with said conduit for moving the same to its several positions of adjustment.

18. A device of the class described, comprising a liquid holding tank having a partition therein, an adjustable conduit projecting into the tank with branches upon each side of the partition, valves adapted to alternately open and close said branches in different positions of adjustment, and means 25 for adjusting the conduit relatively to the valves.

19. A device of the class described, comprising a liquid holding tank having an adjustable conduit projecting therein, a 30 valve housing upon the conduit within the tank, a member fixed upon the housing having an aperture therethrough adapted to communicate with the conduit, a valve stem engaging the tank and extending into said 35 housing and provided with a valve for opening and closing said aperture when the conduit is raised and lowered, yielding means exteriorly of the conduit for holding said valve closed when the conduit is raised, and 40 means for adjusting said conduit relatively to said valve.

20. The combination with a suction producing apparatus and a vacuum gravity feed tank connected therewith, of a liquid 45 fuel supply tank having a partition therein, a conduit connected with said gravity feed tank and having a branch pipe extending into said supply tank upon each side of said partition, an automatic valve for each 50 of said pipes, and means for moving said pipes to effect the alternate opening and closing of said valves.

21. The combination with a suction producing apparatus and a vacuum gravity 55 feed tank connected therewith, of a liquid fuel supply tank having oppositely arranged compartments, a conduit leading from said gravity feed tank having a connection communicating with each of said 60 compartments, an automatic valve for each of said connections, and common means for shifting said connections to effect the alternate opening and closing of said valves.

22. The combination with the manifold

and carbureter of an automobile engine and 65 a vacuum gravity feed tank connected with the same, of a liquid fuel supply source, a fuel reserve supply source, connections between said fuel supply sources and said vacuum gravity feed tank, an automatic 70 valve for each of said connections and means for moving said connections to permit the alternate opening and closing of said valves.

23. The combination with the manifold and carbureter of an automobile engine and 75 a vacuum gravity feed tank having connections leading to said manifold and said carbureter, of a main liquid fuel supply source, a fuel reserve supply source, adjustable connections between said fuel supply 80 sources and said vacuum gravity feed tank, an automatic valve for each of said connections, and means for adjusting the connection to permit the alternate opening and closing of said valves.

24. The combination with the manifold and carbureter of an automobile engine and a vacuum gravity feed tank having connections leading to said manifold and to said carbureter, of a liquid fuel supply tank having a partition therein, a conduit connected with said gravity feed tank having a branch pipe extending into said supply tank upon each side of said partition, an automatic valve for each of said branch pipes, and 90 means for shifting said branch pipes to effect the alternate opening and closing of 95 said valves.

25. The combination with the manifold and carbureter of an automobile engine and a vacuum gravity feed tank having connections leading to said manifold and to said carbureter, of a liquid fuel supply tank having a partition therein, an adjustable conduit connected with said gravity feed tank 100 and having two branch pipes fixed thereon, one of which extends into the supply tank upon one side of the partition and the other upon the opposite side thereof, a valve for each of said branch pipes, and means for adjusting said conduit to effect the alternate 105 opening and closing of said valves.

26. The combination with a suction producing apparatus and a vacuum gravity feed tank connected therewith, of a liquid fuel 115 supply tank having a partition therein, an adjustable conduit connected with said gravity feed tank and having a branch pipe extending into said supply tank upon each side of said partition, and means for automatically effecting the alternate opening and closing of said branch pipes upon adjustment of said conduit.

27. The combination with a suction producing apparatus and a vacuum gravity feed 125 tank connected therewith, of a liquid fuel supply tank having oppositely arranged compartments, an adjustable conduit lead-

ing from said gravity feed tank having a connection communicating with each of said compartments, and means for alternately opening and closing said connections upon 5 adjustment of said conduit.

28. The combination with the manifold and carburetor of an automobile engine and a vacuum gravity feed tank connected with the same, of a liquid fuel supply source, a 10 fuel reserve supply source, adjustable connections between said fuel supply sources and said vacuum gravity feed tank, and means for alternately opening and closing said connections upon adjustment of the 15 same.

29. A device of the class described, comprising a tank having oppositely arranged liquid holding compartments, a conduit leading to said tank, an adjustable member 20 communicating with said conduit and having a branch pipe leading to and movable within each of said compartments, and means for effecting the alternate opening and closing of said branch pipes upon movement of said adjustable member in opposite directions.

30. A device of the class described, comprising a tank having oppositely arranged liquid holding compartments, a conduit 30 leading to said tank, an adjustable member communicating with said conduit and having branch pipes movable therewith and leading to said compartments, means for effecting the alternate opening and closing 35 of said branch pipes upon movement of said adjustable member in opposite directions, and a suction producing apparatus connected with said conduit.

31. A device of the class described, comprising a tank having oppositely arranged liquid holding compartments, a conduit leading to said tank, an adjustable member 40 communicating with said conduit and having a branch pipe leading to each of said compartments, valves coöperating with said branch pipes to control the supply of liquid therethrough, a lever connected with said adjustable member for moving the same to effect the alternate opening and closing of

the valves, and an aspirator connected with 50 said conduit.

32. A device of the class described, comprising a tank having oppositely arranged liquid holding compartments, a conduit leading to said tank, an adjustable member 55 communicating with said conduit and having a branch pipe leading to each of said compartments, spring-seated valves coöperating with said tank and said branch pipes to control the passageways therethrough; 60 means for moving said adjustable member to effect alternate opening and closing of the valves, and an aspirator connected with said conduit.

33. A device of the class described, comprising a liquid fuel tank, an outlet conduit having two extensions adjustable within the tank, and valves adapted to alternately open and close said extensions when moved from one position of adjustment to another. 65

34. A device of the class described comprising a fuel tank, an outlet conduit adjustable therein, a valve for opening and closing said conduit having a stem, said 70 valve and stem being movable with the conduit and relatively to the tank, said stem coöperating with the tank to open the valve when the conduit is moved to one position of adjustment, and means adapted to close the valve when the conduit is moved to another position of adjustment. 75

35. A device of the class described comprising a fuel tank, an outlet conduit adjustable therein, a valve for opening and closing said conduit having a stem, said 85 valve and stem being movable with the conduit and relatively to the tank, said stem coöperating with the tank to open the valve when the conduit is moved to one position of adjustment, means adapted to close the 90 valve when the conduit is moved to another position of adjustment, and a suction producing apparatus connected with said conduit.

In testimony whereof we affix our signatures. 95
